DESIGN FOR A COMBINATION TABLE AND
FOLDABLE BENCHES

Joseph C. Higgins, Chicago, Ill.

Application June 2, 1947, Serial No. 139,399

Term of patent 14 years

(Cl. D33—14)

To all whom it may concern:

Be it known that I, Joseph C. Higgins, a citizen of the United States, residing at Chicago, in the county of Cook and State of Illinois, have invented a new, original, and ornamental Design for a Combination Table and Foldable Benches, of which the following is a specification, reference being had to the accompanying drawing, forming part thereof.

In the drawings:

Figure 1 is a perspective view of a combination table and foldable benches, in open or operative position, showing my new design.

Figure 2 is an end elevation of the combination table and foldable benches, in its closed or inoperative position.

I claim:

The ornamental design for a combination table and foldable benches, as shown.

JOSEPH C. HIGGINS.
